CLAIM

The ornamental design for a tightening tool, as shown and described.

DESCRIPTION

FIG. 1 is a front, top, and right side perspective view of a tightening tool showing our new design;

FIG. 2 is a rear, top, and right side perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The portions of the tightening tool in broken lines are shown for illustrative purposes only and form no part of the claimed design.
